UNITED STATES PATENT OFFICE.

RUSSELL S. BROWN, OF BROOKLYN, NEW YORK, ASSIGNOR TO NEWMAN CLOCK COMPANY INC., OF NEW YORK, N. Y., A CORPORATION OF NEW YORK.

TIME REGISTER.

Application filed January 17, 1922. Serial No. 529,956.

To all whom it may concern:

Be it known that I, RUSSELL S. BROWN, a citizen of the United States, residing in Brooklyn, county of Kings, and borough of Brooklyn, and State of New York, have invented certain new and useful Improvements in Time Registers, of which the following is a full, clear, and exact description.

10 This invention relates to watchman's time clocks and has for one of its principal objects to provide a clock in which the clock movement is in the form of a unit and the recording registering mechanism is in the 15 form of a unit and in which either unit may be removed from the clock casing without removing the other unit.

Another object is to provide a watchman's time clock in which clock movement 20 mechanism, mounted within the clock casing, may be entirely removed from the casing without disturbing registering mechanism, mounted within the casing, and in which registering mechanism mounted within 25 in the casing may be entirely removed from the casing without disturbing the clock movement mechanism.

Referring to the drawings which illustrate what I now consider a preferred form 30 of the invention:

Fig. 1 is an elevation, largely in section, of one form of watchman's clock, or time register, embodying the invention.

Fig. 2 is a section taken substantially on 35 the line 2—2 of Fig. 1.

Fig. 3 is a rear view of the clock with the door open and certain of the parts removed.

Fig. 4 is a view similar to Fig. 3, but containing certain of the parts omitted in 40 Fig. 3.

Fig. 5 is an edge view of the registering unit and a part of the clock door, some of the elements being shown in section.

Fig. 6 is a view of a card or record surface, certain of the indicia being omitted.

Fig. 7 is a perspective view of one of the watchman's keys.

The invention comprises generally—a clock movement unit 10, a recording or registering unit 11, and a casing 12 for both units. This casing or housing herein illustrated is in the form of a cylindrical box

the face of which is provided with a glass window 13, held in position by a bezel ring 14 detachably secured to the inside of said face. The casing 12 comprises also a back door 15, hinged at 16 to said casing, and provided with a locking pin 17 adapted to enter a lock 18 secured to the inner side wall of the casing. The lock 18 may be locked or unlocked by a key (not shown) insertible through the key hole 19.

The clock movement unit comprises a housing 20 in which the now well known clock train is mounted, said housing being detachably secured to and carried by a plate 21. Opposite the plate 21, the housing 20 has secured thereto a clock dial 22 with which the hands 23 (operated by the clock train) are adapted to cooperate to indicate the time. When the unit 10 is mounted in the casing, as hereinafter described, the dial 22 and hands 23 are visible through the window formed by the glass 13 and bezel ring 14. The clock train is shown provided with a winding spindle 25, a setting spindle 26, and a fast-or-slow adjusting spindle 27, all of which project through the plate 21 and are therefore accessible from the rear of the clock when the door 15 is open. The clock train is provided also with an arbor 28 which is rotated thereby uniformly at a predetermined rate, say one revolution in twenty-four hours. This arbor 28 projects through the plate 21 and has secured thereto a base or support 29 adapted to receive a record card or other suitable record surface 30. It will be noted that the base 29 is provided with a plurality of angularly spaced ribs or lugs 31 adapted to enter corresponding notches in the record card and in order to aid the operator in correctly positioning a card on its support 29 one of the ribs is shown provided with an arrow which aligns radially with a corresponding indicating symbol on the card when the latter is correctly positioned. A head 32 is detachably secured to the arbor 28 and serves as a means for detachably holding a card upon the support or base 29.

The recording or registering unit is shown as comprising a plate portion 33 to which is secured, integrally or otherwise, a bracket 34. The bracket 34 is provided

with a sleeve 35 open at one end to receive the shank 36 of a suitable record-controlling key 37, said sleeve 35 having a longitudinal slot 38 to permit the required rotatable movement of a key inserted therein. The plate 33 has secured thereto, preferably detachably, a plate 39, the two plates being spaced apart to permit entry of the record card when the clock is assembled and in use. The plate 39 carries a matrix 40 which constitutes one element of a recording, registering or printing couple. While the other element of such couple might also be carried by or embodied in the registering unit 11, I prefer to illustrate a device in which the said other element 41 or elements are carried by the key or keys 37.

The plate 33 has secured thereto a bracket 42 carrying a pivoted yoke 43 which in turn rotatably supports a roller 44. The yoke 43 and consequently the roller 44 are so biased by means of a spring 45, toward a key inserted into sleeve 35 that on rotational movement of the key the edge 46 of the key will engage the roller, compress the spring, and the key be subsequently snapped by the spring and roller into engagement with the matrix or a record card, if one of the latter is mounted in the clock.

The key 37 (and all others of the set of keys adapted to be used with the particular clock) is provided with a depression 47 adapted to receive a pin or lug 48, mounted on the under side of the bracket 34, when the key is snapped into record-producing position. If it is attempted to employ a key having no depression 47, or a key whose depression is not adapted to register with the particular pin 48, the said pin 48 will prevent the recording element 41 from engaging the record surface or matrix.

As above stated, one of the principal objects of the present invention is to provide an organization in which either the registering unit 11 or the clock movement unit 10 may be removed from the casing 12 without removing the other of said units. A preferred structure by which this result may be accomplished is illustrated in the drawings and may be constructed substantially as follows:

The casing 12 is shown provided with three angularly spaced lugs 70, which may be die cast integrally with the casing. Each of these lugs is formed with a flat or table top upon which the plate 21 is adapted to seat or rest. Each of the lugs 70 is provided with a tapped hole 71 adapted to receive a corresponding screw 72 adapted to pass through a corresponding one of three openings 73 provided in the plate 21. Similarly the casing 12 is provided with lugs 80 having flat tops upon which the plate 83 of the registering unit 11 is adapted to

rest. As in the case of the clock movement unit, the lugs 80 are provided with tapped holes 81 adapted to receive screws 82 which pass through openings 83 in the plate 33. The assembly, operation and disassembly 70 of the clock illustrated will now be briefly described.

Either of the units 10 or 11 may be placed in casing first or, if desirable, both units may be inserted together. The parts are 75 so moved or adjusted that the holes 73 register with the holes 71 and holes 83 register with the holes 81. The screws 72 and 82 are screwed home. A record card 30 may then be mounted on the support 29 80 and held thereon by the head 32. The card will extend between the plates 33 and 40. The casing door 15 may then be closed. After closure the door 15 is locked at 17-18. The watchman, in making his rounds, 85 visits his various stations. At each station he will find a key bearing an imprint or recording element 41 corresponding to that particular station, for example, the key 37 would be at station "10". The watchman will insert the key 37 through the key hole 90, in casing 12, into the registering unit 11 and by rotating the key a record or imprint is made upon the card 30, as above explained. The key is then withdrawn and 95 the next station visited, and so on.

If either of the units 10, 11, in the clock becomes inoperative or disorganized it may be readily removed without removing or disturbing the other unit, by removing the 100 screws 72 or 82. The particular unit or units removed, may then be repaired and remounted in the clock, or replaced by another unit or units.

By virtue of my invention, reinsertions 105 or replacements of the movement unit 10, or registering unit 11, may be made by anyone. The number of stock parts is greatly reduced and various other now apparent improvements effected.

What I claim is:

1. A watchman's recording time clock comprising in combination, a clock movement unit; a registering unit; a casing for said units; and means, detachably connecting said units to said casing, whereby either unit may be removed from said casing without removing the other unit.

2. A watchman's recording time clock comprising, in combination, a clock movement unit including a record surface support and means for actuating the same; a registering unit including at least one element of a recording couple; a casing for said units; and means, detachably connecting said units to said casing, whereby either unit may be removed from said casing without removing the other unit.

3. A watchman's recording time clock comprising in combination; a clock move-

ment unit; a registering unit, a casing for said units; and means, detachably connecting said units to said casing, whereby either unit may be removed from said casing without disturbing the other unit.

4. A watchman's recording time clock comprising in combination, a clock movement unit including a record surface support and means for actuating the same; a registering unit including at least one element of a recording couple; a casing for said units; and means, detachably connecting said units to said casing, whereby either unit may be removed from said casing without moving the other unit with respect to the casing.

5. A watchman's recording time clock as set forth in claim 1 in which either unit is removable from the same side of the casing as the other unit.

6. A watchman's recording time clock as set forth in claim 2 in which either unit is removable from the same side of the casing as the other unit.

7. A watchman's recording time clock as set forth in claim 3 in which either unit is removable from the same side of the casing as the other unit.

8. A watchman's recording time clock as set forth in claim 4 in which either unit is

removable from the same side of the casing as the other unit.

9. A watchman's recording time clock as set forth in claim 1, in which the movement is provided with a substantially segmental plate, and in which the registering unit is provided with a substantially segmental plate, said two plates supplementing each other to form a partition across the clock casing.

10. A watchman's recording time clock as set forth in claim 2, in which the movement is provided with a substantially segmental plate, and in which the registering unit is provided with a substantially segmental plate, said two plates supplementing each other to form a partition across the clock casing.

11. A watchman's recording time clock comprising in combination, clock movement mechanism, registering mechanism, a casing for said mechanisms; and means, detachably connecting said mechanisms to said casing, whereby either mechanism may be entirely removed from said casing without disturbing the other mechanism.

In testimony whereof I hereto affix my signature.

RUSSELL S. BROWN.
